ALFRED F. MASURY, OF NEW YORK, N. Y., ASSIGNOR TO INTERNATIONAL MOTOR COMPANY, OF NEW YORK, N. Y., A CORPORATION OF DELAWARE.

SHEET-METAL INTERNAL-COMBUSTION ENGINE.

1,287,386.

Specification of Letters Patent. Patented Dec. 10, 1918.

Application filed June 21, 1917. Serial No. 176,045.

To all whom it may concern:

Be it known that I, ALFRED F. MASURY, a citizen of the United States, and residing in the borough of Manhattan of the city of New York, county of New York, in the State of New York, have invented certain new and useful Improvements in Sheet-Metal Internal-Combustion Engines, of which the following is a specification, reference being had 5 to the accompanying drawings, forming a part hereof.

This invention relates to internal combustion casings formed of sheet metal and has for its general object to provide a construction 15 in which the sections of the casing may be pressed readily into symmetrical parts from integral blanks and then united permanently to form the complete casing. Internal combustion engine casings of this 20 type while possessing many mechanical advantages over cast structures are difficult to manufacture in such form as will satisfy manufacturing considerations and at the same time give the necessary strength and 25 durability for coöperation in service. The improved construction contemplates one form of casing in which the cylinder section walls and crank case walls are formed of two 30 integral sections united permanently along a transverse plane passing substantially through the mid-section of the motor. In each section the crank case walls and cylinder section walls are integral with one another and the proximate edges of the two 35 sections are flanged to permit their permanent union and the formation of the unitary engine body. Within the cylinder section walls may be supported the other elements such as the cylinders and the top and bottom 40 plates by which the cylinders are supported and the water jackets formed while the crank case may be so shaped as to afford adequate support for the bearings of the crank shaft. The details of the proposed 45 construction will appear more clearly from the illustrated embodiment, in which,—

Figure 1 is a somewhat conventional view of a sheet metal casing embodying the present improvements and showing the walls 50 partly in side elevation and partly in vertical section.

Fig. 2 is a view in transverse section through the casing shown in Fig. 1, taken along the plane indicated by the broken line

2—2 of Fig. 1 and looking in the direction 55 of the arrows.

Fig. 3 is a view in plan taken along the plane indicated by the line 3—3 and looking in the direction of the arrows, the engine head being removed.

The drawings show the improved casing somewhat conventionally, all of the usual operating parts of the motor being omitted in the interest of clearness. The head A may be of cast construction and carry the necessary valve units but this head need not be described in detail since the invention is not concerned with its form or the means for applying it to the improved casing. The cylinder section of the casing consists of two 60 symmetrical sections indicated generally by the reference characters *a* and each of these sections includes side walls *a'*, end walls *a''* integral with the said side walls, end walls *a'''* for the crank case, and side walls *a''''* therefore, all of the said walls in each such section being stamped from a single integral blank and pressed to shape by any suitable devices available in the art for handling metal. Each section has formed in the end walls *a'''* 65 of the crank case a suitable opening *a''''* to receive the bearings for the crank shaft. The sections along their proximate edges are preferably flanged throughout their length, as indicated at *a''''*, and these flanges upon assembling of the motor are brought into snug 70 engagement with one another and united permanently throughout their length as by means of rivets *a''''* or by welding, or in any other way known to the art. In addition to 75 the openings *a''''* for the bearings of the crank shaft the walls *a''''* of the crank case may have stamped therein suitable hand holes *a''''* as is 80 usual in crank case constructions.

Within the engine walls proper there may 85 be supported adjacent the top and bottom horizontal plates *b* in which are formed openings *b'* aligned in the respective plates to receive the cylinders *c* of the motor. These plates are supported within the sheet 90 metal walls of the casing by riveting, welding or otherwise, and the cylinders *c* may be secured in their respective openings in the top and bottom plates by some such method. When the parts are given their permanent 95 set after formation of the engine body it is necessary, of course, that the top and bottom plates *b* shall be so disposed with relation 100 105

to the engine walls and crank shaft and the cylinders so mounted in said plates that the cylinders shall be maintained in parallelism and in proper relation to the moving parts 5 of the motor.

The construction described has the advantage that the two sections *a* may be pressed from a single blank of sheet metal, the walls of the engine and the crank case 10 in each section being integral, and that these two sections may be readily united along the transverse line of union indicated by the flanges *a*.

It is to be understood that the invention 15 is not to be limited to the precise form or size of any of the parts mentioned nor to the particular means employed for uniting any of the contracting metallic parts since all such details will depend upon the 20 character of the motor to be formed and to metal working considerations which may best be optional with those skilled in that particular art.

I claim as my invention:

- 25 1. A sheet metal casing for an internal combustion engine formed of sections united along transverse planes, the walls of the cylinder section and the crank case in each section being formed in one integral piece 30 from a single piece of sheet metal.
2. A sheet metal casing for an internal combustion engine formed of two sections united along a transverse plane passing substantially through the mid-section of the

engine, the walls of the cylinder section and 35 the crank case in each section being formed from a single piece of sheet metal.

3. A sheet metal casing for an internal combustion engine formed of two sections 40 united along a transverse plane passing substantially through the mid-section of the engine, the walls of the cylinder section and the crank case in each section being formed from a single piece of sheet metal, with 45 openings formed in the end walls of the crank case to receive the crank shaft.

4. A sheet metal casing for an internal combustion engine formed of sections united along transverse planes, the walls of the cylinder section and the crank case in each 50 section being formed in one integral piece from a single piece of sheet metal, and top and bottom plates secured permanently within the engine walls and having alined 55 openings to receive the cylinders.

5. A sheet metal casing for an internal combustion engine formed of sections united along transverse planes, the walls of the cylinder section and the crank case in each section being formed in one integral piece 60 from a single piece of sheet metal, with flanges formed along the proximate edges of adjacent sections, and means to secure the flanges together.

This specification signed this 19th day of 65 June, A. D. 1917.

ALFRED F. MASURY.
